Primary Examiner—Alan P. Douglas**Assistant Examiner—Jeffrey Asch****Attorney, Agent, or Firm—William J. Ruano****[57] CLAIM**

The ornamental design for a knock down shelving unit, as shown and described.

DESCRIPTION

FIG. 1 is a top, front, and left side perspective view of a knock down shelving unit showing my new design; and,

FIG. 2 is a bottom, rear, and left side perspective view thereof, the right side being a mirror image of the left side shown.

FIG. 1

FIG. 2
